UNITED STATES PATENT OFFICE.

ALFRED N. GOLDSMITH, OF MOUNT VERNON, NEW YORK, ASSIGNOR TO RADIO CORPORATION OF AMERICA, A CORPORATION OF DELAWARE.

ANTENNA.

Application filed January 11, 1923. Serial No. 611,942

This invention relates to antennæ and particularly to loop antennæ designed for use in dwellings in the reception of broadcasted speech or music.

Under many conditions of indoor reception, as, for instance, in apartment houses, it is much more convenient to use an indoor antenna than an outside one. Indoor antennæ, by reason of the restricted space available, are generally of the loop type. Heretofore, whenever an antenna has been used in a room of a dwelling, the dimensions of the antenna have had to be very small because large loops of known construction and arrangement are not only bulky, unsightly and easily damaged, but they also interfere with the normal use of the room. The use of a small loop, however, is very disadvantageous, because such loops are extremely poor receivers of energy and require excessive amplification in order to enable sufficiently loud signals to be obtained.

It is an object of this invention to provide an antenna of the loop type which may be installed within a room of a dwelling and which will be free from the disadvantages of such antennæ as heretofore constituted. A further object of the invention is to provide a loop antenna, which is limited in size only by the dimensions of the room, which may be readily installed, and which is pleasing to the sight and very compact.

To this end, I provide a strip of flexible material which may be run around a wall of a room in the form of a loop and to which are attached a number of wires extending longitudinally of the strip and connected so as to form a continuous coil or loop of large dimensions and consequently excellent receiving properties.

In accordance with a further feature of the invention, the strip of flexible material constituting the base of the antenna structure is provided with means for facilitating the attachment of the strip around the wall of a room. Such means may, for example, be in the form of tabs projecting outwardly from the edges of the strip.

A still further feature of the invention resides in the combination with an antenna comprising a strip of flexible material and wires extending along the strip of means permanently mounted around the wall of a

room for supporting the strip within the room. The supporting means may conveniently be in the form of an ornamental molding formed with a channel to receive the antenna and so constructed that the antenna when in place on the molding is invisible.

Still another feature of the invention resides in the provision with a strip of flexible material adapted to be attached about a wall of a room and having wires arranged along the strip in substantially parallel relation, of means for connecting the ends of the wires so as to form a continuous loop capable of use as an antenna.

Other objects and features of the invention will appear as the description proceeds and will be pointed out in the appended claims.

In the drawings, in which like reference numerals designate like parts throughout the various views:

Fig. 1 is a view in perspective of an antenna embodying the invention;

Fig. 2 is a view in transverse section along the line 2—2 of Fig. 1;

Fig. 3 is a view in transverse section of an antenna of modified form;

Fig. 4 is a view in elevation of a wall of a room having the invention applied thereto;

Fig. 5 is a view in vertical section along the line 5—5 of Fig. 4;

Fig. 6 is a view in horizontal section substantially along the line 6—6 of Fig. 5.

Fig. 7 is a diagrammatic view of a terminal block whereby the wires on a flexible strip may be connected into a continuous spiral coil;

Fig. 8 is a view similar to Fig. 7 but showing the wires adjacent to the opposite edges of the strip disconnected from the circuit of the coil so as to reduce the inductance of the antenna;

Fig. 9 is a view similar to Fig. 8, but showing means for connecting the outer wires of the loop structure in parallel so as to cause the inductance effects of the wires to balance each other;

Fig. 10 is a view in perspective of a portion of the strip, showing tabs formed integrally therewith for facilitating attachment of the strip around the wall of a room;

Fig. 11 is a view similar to Fig. 10 but

illustrating the use of gromets inserted into the tabs;

Fig. 12 is a section along the line 12—12 of Fig. 11; and

5 Fig. 13 is a view in perspective of two antennae arranged at right angles to each other so that non-directional reception can be effected by their selective use.

The illustrated construction comprises a 10 strip 10 of flexible material having wires 12 extending longitudinally of the strip in substantially parallel relation. As shown in Figs. 1 and 2, the strip 10 consists of woven fabric of which the wires 12 constitute the warp, and the weft or transverse threads of which serve to maintain the wires 12 in spaced relation and to prevent contact of the wires. The weft of the fabric may be of textile material and should be of low 15 electrical conductivity so as to insulate the wires from each other. The wires 12 may, of course, also be individually insulated.

It is recognized that the material of 20 which the strip 10 is composed, and the manner of mounting the wires 12 on the strip may vary widely. For example, the wires 12 may be secured to one of the lateral surfaces of the strip 10 by glue, Fig. 3, or any other suitable means. Moreover, the 25 wires 12 may fastened in one or more layers either to a single strip as shown in Figs. 2 and 3 or to several parallel strips. If desired, the wires 12 may be bundled into a strip in any other desired fashion without 30 departing from the principles of the invention, so long as a construction is provided in which a number of parallel wires is mounted on a flexible supporting structure which can be run around a wall of a room. The material into which the wires are 35 attached is preferably such as to be of low dielectric constant and have small radio frequency losses.

In the practice of the invention, it is 40 contemplated that the structure composed of the strip 10 and the wires 12 will be manufactured in the form of continuous rolls, and that a person desiring to construct an antenna will purchase a roll or section of 45 a roll of a length determined by the dimensions of the room in which he wishes to install the antenna. In such a case, in the setting up of the antenna, means are employed for connecting the ends of the wires 50 12 so as to form them into a continuous spiral coil. Such means may conveniently comprise a terminal block 14 provided with two parallel rows of contacts 16 which may 55 be in form of binding posts to which the ends of the wires 12 may be connected. In the use of a terminal block, such as is shown in Fig. 1 of the drawings, wherein the number of contacts 16 in each of the rows is equal, and the corresponding contacts in 60 the two rows are oppositely disposed, the

contacts will be joined by parallel diagonal connections 18 to the end that a continuous coil may be provided. The connections 18 will be one less in number than the wires 12. Contacts 16' and 16'' at opposite ends 70 of the rows of contacts are not joined to any of the connections 18. The last-mentioned contacts are, on the contrary connected respectively to wires 24 and 26 one of which constitutes an input connection to 75 and the other an output connection from the antenna.

If desired, however, a strip 10 may first be formed into a loop, after which a single length of wire may be wound about the loop 80 thus formed so as to provide an antenna, the separate loops of which are arranged in substantially parallel relation along the strip and are attached thereto in any suitable manner. In such a case, the use of a terminal block such as that designated 14 is not required, it being only necessary that input and output connections be provided for the ends of the wire coil.

Manifestly, the invention may be embodied in an antenna comprising only a single turn or loop of the antenna structure, composed of the strip 10 and the wires 12 and hereinafter referred to as the "composite strip." As shown in Fig. 1, however, an inner turn 28 and an outer turn 30 of the composite strip are employed, and it is obvious that as many of such turns as are desired may be used. If it is desired to construct an antenna of greater length than a 100 composite strip in the possession of the user, as, for example, when an antenna is first installed consisting of a single turn of the composite strip corresponding with the dimensions of a room, and it is desired to 105 increase the size of the antenna by the addition of another turn of the strip, the ends of the wires 12 of one of the turns may be connected with the ends of the wires of the other turn by means including a terminal 110 block 32 having two rows of contacts 34 and connections 38 between the oppositely disposed contacts of the two rows. As in the case of the contacts 16 of the terminal block 14, the contacts 34 of the terminal 115 block 32 are preferably provided in the form of binding posts to which the connections 38 and the ends of the wires 12 of the composite strips may be secured.

In the installation of a composite strip 120 constructed in accordance with the invention around a wall of a room so as to serve as an antenna, the strip may be secured to the wall in any suitable manner, and all portions of the strip may be painted or otherwise given 125 a color corresponding to that of the surfaces of the room contiguous to the portions of the strip. In this way the antenna can be rendered not only inconspicuous but practically invisible. Moreover, it is possible that 130

a pleasing color arrangement may be obtained in which some or all of the portions of the antenna are of different color from the contiguous surfaces of the room.

5 In some respects, it is advantageous to provide means permanently mounted on or around a wall of a room for supporting the antenna of this invention. A preferred embodiment of such means is shown in Figs. 4, 10 5 and 6 and comprises a molding 40 composed of wood or other non-conductive material and formed with a channel 42 within which the composite strip or antenna may be housed so as to be invisible. An important 15 advantage obtained by the use of the molding 40 for supporting the antenna is that losses through the plaster or column of a room may thereby be reduced. By making the rear flange 44 of the molding 40 of considerable 20 thickness, losses through the wall of a room may be practically eliminated. In the event that a molding arranged around a wall of a room, as shown in Fig. 4, is employed for supporting the antenna, the terminal block 25 14 for connecting the ends of the wires 12 so as to form them into a continuous coil is preferably mounted on an adjacent wall of the room, a notch 46, Fig. 6, being formed in the front flange 48 of the molding 40 through 30 which the ends of the wires 12 may be bent outwardly for connection with the contacts 16 of the terminal block. For the sake of attractiveness of appearance, the terminal block 14 may be provided with a casing 50 35 which matches with the front face of the molding 40 as shown in Fig. 6.

In order to facilitate the attachment of the composite strip either directly to a wall of a room or to the molding 40, the strip 10 40 may be provided at either or both of its edges with outwardly projecting tabs 52, Figs. 10 and 11, adapted to receive a nail or 45 other suitable fastening. The tabs 52 may be formed integrally with the strip 10, as shown in the drawings, or may be attached thereto in any suitable manner. If desired, gromets 54 may be inserted in the tabs 52 to reinforce them against being torn away from the fastenings.

50 The inductance of the antenna may, if desired, be decreased by the omission from the terminal block 14, Fig. 8, of the outer connections 18 appearing in Figs. 1, 5 and 7 and by attaching the input and output connections 24 and 26 respectively to binding posts 16 spaced inwardly from the ends of the rows of binding posts, so as to cut out one or more of the outer turns of the wire coil. The outer turns of the wire coil which are 55 thus cut out of the circuit of the antenna may exert injurious inductive effects. Such effects may be balanced or nullified by connecting the uncircuited, outer wires in parallel by means of connections 56 and 58 as 60 shown in Fig. 9.

As is well known, an antenna of the kind shown in Fig. 1, when installed on a wall of a room receives best from a station lying in the extended plane of such wall and receives least efficiently from a station lying in a 70 direction at right angles to such plane. In other words, the antenna is of the type known in the art as directional. In order to provide an antenna which will receive signals efficiently from all directions, a composite strip 10', Fig. 13, made in accordance 75 with this invention may be mounted on one wall of a room as hereinbefore described, and a similar strip 10'' may be mounted on an adjacent wall of the room at substantially 80 right angles to the first-mentioned strip, each of the antenna sections 10' and 10'' thus formed being provided with individual input and output connections. Such an arrangement enables non-directional reception, 85 inasmuch as the antenna section which is found to afford best signals may be connected with the receiving apparatus. In order to receive most efficiently from stations which are not located in the extended plane 90 of either of the sections 10' and 10'' of the antenna, but in a position intermediate between the planes of the sections 10' and 10'', such sections may be connected in series to 95 form the antenna. The antenna thus formed will receive best in directions bisecting the angles between the planes of the sections 10' and 10''.

An antenna constructed and installed as hereinbefore described, whether it is attached directly to a wall of a room or supported on a molding such as the molding 40, shown in the accompanying drawings, will afford much better reception than a small loop antenna of the kind hereinbefore employed in dwellings.

Having described my invention, what I claim is:

1. A loop antenna comprising a strip of flexible material, wires arranged in substantially parallel relation along the strip, means projecting outwardly from the edges of the strip for facilitating its attachment to a wall of a room, and means for connecting the ends of the wires so as to form them into a 110 continuous, spiral coil.

2. In a device of the class described, a strip of flexible material having tabs formed integrally therewith and extending outwardly from its edges for facilitating attachment 120 of the strip to a wall of a room, wires arranged in substantially parallel relation along the strip, and means for connecting the ends of the wires so as to form them into a continuous coil.

3. In a device of the class described, a strip of flexible material of relatively great length and small width, wires arranged in substantially parallel relation longitudinally 130 of the strip and connected at their ends so

as to form a continuous coil and means for supporting the antenna within a room of a building, said means comprising a molding permanently secured about one of the walls of the room and constructed to provide a channel within which the strip may be housed so as to be invisible.

4. In a device of the class described, a strip of flexible material, wires arranged in substantially parallel relation along the strip, a molding arranged around one of the

walls of a room for supporting the strip within the room, a terminal block mounted on an adjacent wall of the room and comprising contacts with which the ends of the wires may be connected, connections between the contacts of the terminal block arranged to join the wires into a continuous coil, an input wire leading to one of the contacts of the terminal block, and an output wire leading from another of such contacts.

ALFRED N. GOLDSMITH.
